UNITED STATES PATENT OFFICE

HARRY O. CRAM, OF BRIDGEPORT, CONNECTICUT

CARBURETOR

Application filed January 21, 1925. Serial No. 3,743.

This invention relates to carburetors for internal combustion engines, an object of the invention being to provide an improved relatively simple and compact carburetor so constructed as to more efficiently and properly supply a correct fuel mixture to the engine throughout the range of operation of the engine.

A further object of this invention is to provide an improved carburetor in which the carbureting or mixing chamber thereof comprises a plurality of separate or independent mixing chambers or ducts having a plurality of inlets through which fuel and air are supplied, and wherein means is provided for varying the capacity of the carbureting chamber by independently closing and opening one of the mixing chambers or ducts in proportion to the requirements of the engine.

One of the features contemplated by this invention is the provision of a carburetor having for instance substantially two separate mixing chambers, one adapted to be used alone when the engine is throttled down fully, and both adapted to be used to capacity when the throttle is wide open. Under operating conditions between these extremes, provision is made for gradually opening or closing one of the mixing chambers in proportion to the requirements of the engine. Provision is also made for utilizing the exhaust gases of the engine to assist in carburetion, the carbureting chamber, comprising a plurality of ducts of different sizes, being surrounded by a heating chamber which is effective to heat the fuel passing through the smaller ducts to a greater degree thereby enabling the fuel mixture to be heated properly under different operating conditions.

Other objects of this invention will appear in the following description and appended claims, reference being had to the accompanying drawings forming a part of this specification, wherein like reference characters designate corresponding parts in the several views, and wherein Fig. 1 is a central vertical section of this improved carburetor; Fig. 2 is a detail sectional view taken substantially on line 4—4 of Fig. 1 looking in the direction of the arrows in said Fig. 1;

Fig. 3 is a cross section taken substantially on line 5—5 of Fig. 1; Fig. 4 is a front elevation of this improved carburetor; and Fig. 5 is a left-hand view of the carburetor shown in Fig. 1.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The carburetor in the present preferred form herein shown and described comprises a body or casing 9 preferably in a single casting and having at opposite sides thereof openings 10 and 11. Within the casing 9 is formed a heating chamber 12. Connected to the openings 10 and 11 which communicate with the heating chamber 12 are pipes 13 and 14 respectively which are secured in place by means of collars 15 bolted to the casing 9 and screwed on to the ends of the pipes, as shown in Fig. 1.

Centrally formed within the casing 9 and surrounded by the heating chamber 12 is a carbureting or mixing chamber 16. In the present instance this comprises a relatively large straight duct 17 terminating at its bottom in an inlet opening 18, and which, because of its size, will be for purposes of designation termed "the main duct or chamber." The carbureting chamber also comprises a series of relatively small ducts 19 which are arranged at one side of and partly around the duct or passage 17 as shown clearly in Fig. 3, and which will be, for purposes of designation, termed "auxiliary or independent ducts." The ducts 19 at the bottom 20 thereof terminate at a point somewhat above the bottom of the duct 17 (see Fig. 1), and open into a chamber 21 which terminates in an inlet opening 22. The inlet openings 18 and 22 are located in the same horizontal plane and in the present instance these openings have substantially the same diameter. Thus it will be seen from this construction that the inlet

55

65

70

75

80

90

95

100

18 for the duct 17 has substantially the same size as the inlet 22 for the several ducts 19. Below the carbureting or mixing chamber the carburetor is provided with an air intake pipe or passage 23. A nipple 24 is located in the end of the pipe 23 and is provided at one side with an opening or orifice 25 through which air is admitted. A sleeve 26 surrounds the nipple 24 and is provided with an opening adapted to register with opening 25. This sleeve is held in position by means of a thumb screw 27, and by loosening the screw the sleeve may be rotated to vary the amount of unheated air admitted into the air intake pipe. Connected to the upper end of the pipe 23 is a casing which is mounted on the exhaust pipe 14 and forms a hot air jacket adapted to heat the air entering the carburetor.

20 The several ducts 17 and 19 at the upper ends thereof terminate in a common opening 29, and the casing 9 is provided with a flanged portion 30 which is adapted to be bolted at 31 to a corresponding flange 32 carried by a pipe 33 which leads to the intake manifold of the engine. Carried by the base portion 34 of the carburetor are a pair of spray nozzles 35 and 36. The orifice 37 of spray nozzle 35 is located within the mouth or inlet 18 of the large duct 17, and the orifice 38 of the spray nozzle 36 is located within the inlet opening 22 for the several ducts 19. It will be noted that the stems of the spray nozzles 35 and 36 are centrally alined with the inlets 18 and 22. These spray nozzles may be of any suitable construction and in the present instance the needle valves controlling the outlet orifices thereof are adjustable by means of handles 39 and 40 respectively. The base portion 34 of the carburetor is bored at 41 and a pipe 42 communicates with this bore for the purpose of supplying the spray nozzles with fuel from a float chamber 51.

45 Located in the outlet 29 is a valve 43 which in the present instance is of the butterfly type. This valve is mounted on a pivot pin 44 extending through the wall of the casing. Connected to the outer end of this pin or spindle 44 is a two-armed lever by means of which the valve 43 is operated. One arm 45 of this lever has the usual operating connection and the other arm 46 is connected by means of a link 47 to a lever or arm 48 secured to a pivot pin 49. This pin or spindle extends through 50 a wall of the casing into the lower end of the duct 17, and connected thereto is a throttle valve 50.

60 From the foregoing it will be noted that upon swinging the lever arm 45 the throttle 43 will be swung on its pivot 44, and at the same time by means of the connections between lever 45 and lever 48 the throttle 50 will at the same time be swung on its pivot 49. The construction of the connecting members between the main throttle 43 and the

auxiliary throttle 50 are such that the latter will be in horizontal position as shown in Fig. 1 when the main throttle 43 is partially open. In this position of the throttle valves the engine will be fully throttled down, the 70 throttle valve 50 acting to close or shut off the duct 17. When the main throttle 43 is in vertical position and wide open the throttle 50 by virtue of the link connections will also be in substantially vertical position and 75 therefore wide open.

When the main throttle 43 is gradually closed thereby decreasing the speed of the engine, the throttle 50 working in conjunction with the main throttle gradually limits 80 or shuts off the flow of fuel and air through the large tube or duct 17. Thus as the speed of the engine decreases the action on the fuel nozzle 35 gradually decreases, or in other words as the speed decreases, the suction is 85 gradually taken away from one nozzle 35 so as to act more fully on the other nozzle 36. When the speed of the engine is lowest, the throttles being in the position shown in Fig. 1, the suction acts entirely on the nozzle 36. 90 The effect of this operation is to insure practically a uniform velocity of air through the inlets 18 and 22 into the carbureting chamber. As the main throttle 43 is opened and the 95 flow of air increases in volume an increasing portion of this volume of air is gradually diverted to the inlet 18 around the nozzle or fuel jet 35, so that when the throttle is wide open the air velocity is the same as when the 100 throttle is closed, since the capacity of the carburetor has been increased in proportion so as to handle the increased volume of air drawn through the intake.

In the present construction it will be noted 105 that I have provided a carbureting chamber which in all substantial respects comprises two separate mixing chambers, one being the tube or duct 17, and the other the several tubes or ducts 19, each thereof having a fuel nozzle. When the throttles are wide open the suction of the engine acts upon both fuel nozzles 35 and 36, and when the engine is throttled down entirely the suction thereof acts 110 upon fuel nozzle 36 alone. Thus, assuming that the combined capacity of the ducts or tubes 19 is the same as the capacity of the duct or tube 17 it will be noted that when the throttles are wide open the main carbureting chamber herein will have twice the capacity 115 as when the engine is fully throttled down. In the case of a 1½ inch carburetor, that is a carburetor in which the outlet passage 29 is 1½ inches in diameter, the combined area 120 of the small passages 19 will be substantially the same as the area of the passage 17 and the combined area of all the passages 17 and 19 125 will be substantially the same as the outlet passage 29 and therefore, when the large passage 17 is closed by the valve 49, the carburetor functions as a carburetor having half 130

the capacity of the carburetor when the passage 17 is open.

This improved carburetor, I have found by actual test under working conditions, will supply the correct proportions or ratio of air and fuel at all times. It is commonly understood that the proper proportions or ratio is 1 to 15, that is 1 of fuel and 15 of air, and in this improved carburetor, substantially this same ratio is maintained thru the small passages 19 when the large passage 17 is closed. In carburetors heretofore in use, the most common means used in trying to maintain this proper ratio when the engine is throttled down is a spring air valve or an auxiliary fuel passage or port, neither of which have been entirely successful, but in the present improvement actual tests have shown that the same ratio or correct proportions of air and fuel are maintained thru the smaller ducts 19 when the engine is throttled down, or when the main passage 17 is fully closed.

From the foregoing it will be noted that in the present carburetor there is no fixed opening at the bottom of the main carbureting chamber under all operating conditions. In this invention the actual capacity of the opening through the carbureting chamber increases and decreases in proportion to the throttled condition of the engine whereby a practically uniform air velocity around the fuel jets is maintained under all conditions. Heretofore in carburetors, the inlet to the carbureting chamber has been fixed under all conditions. The incoming air passing through this opening varied in velocity in proportion to the R. P. M. of the motor, and hence the fuel jet located at this opening was subjected to widely varying pressures, and it has been found that the varying action on the fuel jet did not enable a properly proportioned mixture to be obtained under different conditions of operation.

Heretofore in order to obtain the correct amount of fuel throughout the different speeds of the engine auxiliary means was provided to compensate for that condition. For instance in some cases spring tension air valves are utilized or in other cases more complicated means employed in an effort to get a correct mixture of air and gasoline under various conditions. That none of these present-day carburetors supply a correct mixture at all times is evidenced by the fact that the great difficulty experienced in present-day engines results from unburned fuel passing down the cylinder walls into the crank case. This has been so serious that the lubricating oil in engines must be withdrawn frequently and a fresh supply substituted.

In the present carburetor a uniform velocity of air around the fuel jets is obtained under all conditions. When the throttles are wide open and the suction of the engine greatest, the air coming through the intake 23 will

enter the mixing chamber through both inlets 18 and 22. When the engine is fully throttled down and the suction is lowest, the air inlet 18 is shut off and the air will pass through inlet 22 alone. At the same time this suction acts upon the single fuel jet 36, and a proper proportion of fuel and air is obtained under all conditions. At the same time it will be noted that the air and fuel will be heated to a greater extent under throttled conditions than under conditions where the throttles are wide open, since when the gases are passing through the small tubes 19 they will be heated to a greater extent, than when passing through the tube 17 as well. Thus, it will be seen that when the engine is gradually throttled down, the capacity of the carbureting chamber is gradually reduced and at the same time the gases are gradually heated to a greater extent.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A carburetor comprising a mixing chamber within a heating chamber, the mixing chamber comprising a main duct having an air inlet and a plurality of independent ducts all having an independent but common air inlet, all of said ducts extending through the heating chamber and having a common outlet, a pair of fuel nozzles, one for each inlet, whereby one nozzle is in communication with one duct and the other in communication with all of the remaining ducts, throttling means for the outlet, and positively controlled means located adjacent to one of said nozzles for gradually or entirely cutting off the supply of fuel from said nozzle.

2. A carburetor having a mixing chamber within a heating chamber, the mixing chamber comprising a main duct having an air inlet and a plurality of independent ducts all having an independent but common air inlet, all of said ducts extending through the heating chamber and having a common outlet, said independent ducts being all located at one side only of the main duct, an independent fuel nozzle for each inlet, throttling means for the outlet, and means interconnected with said throttling means located at the lower end of one duct and adjacent to one of said nozzles for gradually or entirely cutting off the supply of fuel from said nozzle.

3. A carburetor having a mixing chamber within a heating chamber, the mixing chamber comprising a main duct having an air

5 inlet and a plurality of independent ducts all having an independent but common air inlet, all of said ducts extending through the heating chamber and having a common outlet, said independent ducts having less length than the main duct, a pair of fuel nozzles, one for each inlet, whereby one nozzle is in communication with one duct and the other in communication with all of the remaining 10 ducts, throttling means for the outlet, and positively controlled throttling means located at the lower end of the longer duct and adjacent to one of said nozzles for gradually or entirely cutting off the supply of fuel from 15 said nozzle.

4. A carburetor having a mixing chamber within a heating chamber, the mixing chamber comprising a main duct having an air inlet and a plurality of independent ducts all 20 having an independent but common air inlet, said inlets having substantially the same size, all of said ducts extending through the heating chamber and having a common outlet, a pair of fuel nozzles, one for each inlet, 25 whereby one nozzle is in communication with one duct and the other in communication with all of the remaining ducts, throttling means for the outlet, and positively controlled means interconnected with said throttling 30 means and located adjacent to one of said nozzles for gradually or entirely cutting off the supply of fuel from said nozzle.

5. A carburetor having a mixing chamber within a heating chamber, the mixing chamber comprising a main duct having an air inlet and a plurality of independent ducts of smaller diameter all having an independent but common air inlet, said inlets having substantially the same size, all of said ducts extending through the heating chamber and having a common outlet, said independent ducts being located to one side of the main duct and having less length than the main duct, a chamber located between said independent ducts and the inlet thereof, an independent fuel nozzle projecting into each inlet, and interconnected valves located adjacent to the outlet and to that nozzle supplying the main duct for throttling the outlet and for 40 gradually or entirely cutting off the supply of fuel from said nozzle, thereby gradually or entirely forcing the fuel through smaller ducts, whereby it becomes more highly heated.

6. A carburetor having a mixing chamber 55 within a heating chamber, the mixing chamber comprising a main duct having an air inlet and a plurality of independent ducts of smaller diameter, all having an independent but common air inlet, all of said ducts extending through the heating chamber and having a common outlet, a pair of fuel nozzles, one for each inlet, whereby one nozzle is in communication with one duct and the other in communication with all of the remaining ducts, and means located adjacent to

70 the outlet and to that nozzle supplying the main duct for throttling the outlet and for gradually or entirely cutting off the supply of fuel from said nozzle and thereby gradually or entirely forcing the fuel through that part of the mixing chamber whereby it becomes more highly heated.

7. A carburetor comprising a mixing chamber formed of a plurality of independent ducts of different diameters having independent air inlets and a common outlet, means for heating said mixing chamber thereby to more highly heat the fuel mixture in one part than in another part thereof, a pair of fuel nozzles, one for each inlet, whereby one nozzle is in communication with one duct and the other in communication with all of the remaining ducts, and means for gradually cutting off one of said ducts thereby gradually reducing the capacity of the mixing chamber and means interconnected with said last means for at the same time forcing the fuel only through the part of the mixing chamber where it becomes more highly heated.

8. A carburetor comprising a mixing chamber formed of a main duct having an air inlet and a plurality of independent smaller ducts all at one side only of said main duct and all having an independent but common air inlet, all of said ducts having a common outlet, means for heating said mixing chamber, an independent fuel nozzle for each inlet, and a pair of interconnected throttle valves one controlling the outlet and the other the nozzle for the main duct and operative to gradually cut off said main duct and thereby gradually reducing the capacity of the mixing chamber and at the same time forcing the fuel to pass only through the smaller ducts whereby it becomes more highly heated.

9. A carburetor comprising a mixing chamber formed of a main duct having an air inlet and a plurality of independent smaller ducts at the side of said main duct and all having an independent but common air inlet, all of said ducts having a common outlet, means for heating said mixing chamber, an independent fuel nozzle for each inlet, a throttle valve located in the outlet, a throttle valve located adjacent to the inlet and nozzle of the main duct, and means connecting said throttle valves for simultaneous operation to cause one of the valves to have a greater range of movement than the other and operative to gradually cut off said main duct and its nozzle and thereby gradually reducing the capacity of the mixing chamber and at the same time forcing the fuel to pass only through the smaller ducts whereby it becomes more highly heated.

10. A carburetor comprising a casing having an air inlet and having within said casing a combined heating and mixing chamber

70

comprising a plurality of independent passages all within the heating chamber, a plurality of said passages having a single inlet and one of said passages having an independent inlet, a common outlet for the fuel mixture from all of said passages, means in said outlet for controlling the quantity of fuel mixture passing therethrough, a pair of nozzles within said casing, each aligned with one of said inlets, means for conveying fuel to the nozzles, and means also within said casing and interconnected with said outlet controlling means for varying the quantity of fuel passing through one passage with relation to said plurality of passages.

11. A carburetor comprising a casing having an air inlet and having within said casing a combined heating and mixing chamber comprising a plurality of independent passages all within the heating chamber and of different diameters whereby the fuel mixture passing through certain of them becomes more highly heated and a plurality of said passages having a single inlet and one of said passages having an independent inlet, a pair of nozzles within said casing for independently supplying fuel to said inlets, and means also within said casing for varying the quantity of fuel through one inlet with relation to the other whereby the fuel will pass through the passages where it becomes more highly heated.

12. A carburetor having therein a mixing chamber within a heating chamber, the mixing chamber comprising a plurality of ducts, means for supplying a mixture of air and fuel to and through said ducts at a certain ratio and heated to a certain degree one of said means in communication with one of said ducts and the other in communication with all of the remaining ducts and positively-controlled connected means for closing certain of said ducts and maintaining the same ratio of air and fuel through the other ducts but heated to a higher degree.

13. A carburetor having therein a mixing chamber within a heating chamber, said mixing chamber comprising a plurality of fuel passageways, means for heating the fuel mixture passing through certain of said fuel passageways to a greater extent than others, means for supplying a mixture of air and fuel to said passageways at a certain ratio and positively-controlled connected butterfly valves for closing certain of said passageways and maintaining the same ratio of air and fuel through the other passageways while increasing the heat of the fuel passing through said last passageways.

14. In a carburetor, a mixing chamber comprising a plurality of fuel passageways of different diameters, means for heating all of said fuel passageways and the fuel passing through certain thereof to a greater extent than others, means for supplying a mixture

of air and fuel through said passageways at a certain ratio, a plurality of needle-valve-controlled fuel supply nozzles and air inlets for independently supplying a mixture of air and fuel to said passageways at a certain ratio, said needle-valves being located at approximately the same level, means for closing one of said passageways adjacent its lower end and maintaining the same ratio of air and fuel through other passageways while increasing the heat of the fuel passing through said last passageways.

15. A carburetor comprising a plurality of heated mixing chambers, each mixing chamber having an inlet and each having substantially the same area, means for supplying air and fuel to said inlets, said mixing chambers having a common outlet substantially corresponding to the combined area of all the mixing chambers, a throttle valve in said common outlet, and a throttle valve connected for operation with first throttle valve for controlling one of said mixing chambers, the organization being such that when said last throttle valve is closed the same ratio of air and fuel will be maintained in the other mixing chamber.

16. In a carburetor, a carbureting chamber within a heating chamber, said carbureting chamber comprising a plurality of separated ducts of different diameters having a common outlet and a plurality of fuel inlets, means for heating all of said ducts and the fuel passing through certain thereof to a greater extent than others, a plurality of fuel nozzles and air inlets for supplying air and fuel to said fuel inlets at a certain ratio, one of said fuel nozzles in communication with one of said ducts and the other in communication with all of the remaining ducts, and means for closing or opening a fuel inlet and thereby the passageways of certain of said ducts and at the same time maintaining the same ratio of air and fuel through the remaining ducts while thereby varying the degree of heat of the fuel mixture passing from the carbureting chamber.

17. A carburetor combining a fuel mixing chamber within a heating chamber, the fuel mixing chamber comprising a main duct having an air inlet and a group of smaller ducts having an independent but common air inlet, all of said ducts passing thru the heating chamber, an independent fuel nozzle for each inlet, a common outlet passage for the fuel mixture from all of said ducts, throttling means for said outlet, throttling means at the lower end of one duct and adjacent to one of said nozzles, and positively controlled means for operating both of said throttling means to gradually or entirely cut off the supply of fuel from said throttle controlled nozzle as the fuel supply from said outlet is gradually but not entirely cut off.

18. A carburetor combining a fuel mixing

chamber within a heating chamber, the fuel mixing chamber comprising a main duct having an air inlet and a group of smaller ducts having an independent but common air inlet, all of said ducts passing thru the heating chamber, an independent fuel nozzle for each inlet, a common outlet passage for the fuel mixture from all of said ducts, throttling means for said outlet, throttling means at the lower end of one of said ducts and adjacent to one of said nozzles, and a single positively controlled means for operating both of said throttling means to gradually or entirely cut off the supply of fuel from said throttle controlled nozzle as the fuel supply from said outlet is gradually but not entirely cut off.

19. A carburetor combining a fuel mixing chamber within a heating chamber, the fuel mixing chamber comprising a main duct having an air inlet and a group of smaller ducts all located to one side only of the main duct and having an independent but common air inlet, all of said ducts passing through the heating chamber, an independent, needle valve controlled, fuel nozzle for each inlet, said needle valves being located at approximately the same level, a common outlet passage for the fuel mixture from all of said ducts, throttling means for said outlet, throttling means adjacent to one of said nozzles, and positively-controlled means for operating both of said throttling means to gradually or entirely cut off the supply of fuel from said throttle controlled nozzle as the fuel supply from said outlet is gradually but not entirely cut off.

Signed at Bridgeport, Connecticut, this 10th day of January, 1925.
